UNITED STATES PATENT OFFICE

HERMAN F. A. BOEHLER, OF EDEN, NEW YORK

DESIGN FOR A VEST OR LIKE ARTICLE OF APPAREL

Application filed July 7, 1930. Serial No. 36,289. Term of patent 3½ years.

To all whom it may concern:

Be it known that I, HERMAN F. A. BOEHLER, a citizen of the United States, residing at Eden, in the county of Erie and State of New York, have invented a new, original, and ornamental Design for Vest or like Article of Apparel, of which the following is a specification, reference being had to the accompanying drawing, forming a part thereof.

The accompanying drawing shows a front view of a vest embodying my new design.

The rear side of the vest is substantially plain and of any suitable outline, the design feature being directed to the front side of the vest and more particularly to the cut of the neck portion thereof as shown in the drawing.

I claim:

The ornamental design for a vest or like article of apparel, substantially as shown and described.

HERMAN F. A. BOEHLER.
